JOINT FOR CONCENTRIC CONDUCTORS

Albrecht Streib, Port Jefferson Station, N. Y.,
assignor to Radio Corporation of America, a
corporation of Delaware

Application December 13, 1938, Serial No. 245,350

5 Claims. (Cl. 287—125)

This invention relates to a new and novel method of joining two lengths of concentric conductors by means of an invisible joint to form one continuous length of conductor of the same diameter throughout.

An object of this invention is to simplify and improve the joints of concentric transmission lines generally.

Another object of this invention is to provide a simple and inexpensive joint which is mechanically strong and gives good electrical conductivity to the line.

Still another object of this invention is to provide a joint for a concentric conductor which permits the change of the conductors without interfering with the electrical characteristics of the line.

In the construction of concentric transmission lines as used in short wave and television circuits, it often becomes necessary to join several lengths of conductors to form the center or inner conductor. When this is done by methods known in the prior art, such as soldering the ends over a plug, the whole length must be handled as a unit, which is difficult to manipulate. Furthermore, when alterations are to be made in the line, the electrical characteristics of the circuit are consequently upset. Also, if screw threads are used, such as tapped inserts and studs, to assemble the line, the whole length of the conductor must be turned as a unit, which also presents installation difficulties. As the inner conductor of a transmission line must be of the same diameter throughout its length, such methods as couplings and flanges known to the plumbing and heating trades, cannot be used.

The purpose of this invention is to provide an improved transmission line employing novel means of readily joining the several lengths of conductors into one continuous length of the same diameter by means of invisible joints. By the use of this invention, the conductors may be broken up into several short lengths, which makes it easier in handling and facilitates more rapid installation. The joining operation of conductors of this invention is very simple and is not accomplished by means known in the prior art, such as applying a Stillson wrench to the tubular conductors, but is accomplished by rotating a spacer which is inserted between the two adjacent conductor ends. The spacer, itself, may be rotated by hand or by means of a strap wrench, so that no rough edges will be left on the conductor to cause brushing to the inner surface of an outer conductor when high voltages are en-

countered. By means of this invention, it will be readily seen that it is not necessary to handle or rotate the conductors in order to join them. They may be placed in their final positions before joining and once in position, may even be held by their insulation members if convenient without hindering the joining operation.

This invention will best be understood by referring to the accompanying drawing, in which:

Fig. 1 is a sectional view of a concentric conductor;

Fig. 2 is a sectional view of an inner conductor with a slightly different binding member;

Fig. 3 is a sectional view of an inner conductor with a still further modification in the binding member;

Fig. 4 is an operative assembly view of one of the inner concentric conductors and the adjustable binding member;

Fig. 5 is a detail of a binding member which is provided with a central bore.

Referring now in detail to Fig. 1 of the drawing, the outer conductor O is shown supporting inner conductors A and B by means of any suitable insulation material, such as a ceramic disc I. Conductor A has inserted in its lower end a block or plug E which is provided with an internal threaded well, an aperture E₁ and a recessed portion E₂. The conductor B is provided with an end plug C, having internal threads C₁. In each case, the plugs C and E are soldered at the ends of the conductor and tapped with internal threads to receive the joining member or bolt D. Also, in both conductors A and B, the opposite ends (not shown) are provided with alternately arranged plugs. That is, if conductor A is provided with plug E in its lower portion, the upper portion will then be provided with a plug C. In contradistinction thereto, conductor B is provided with plug C in its upper portion and the lower portion will be provided with a plug E. Joining member D has a Woodruff key K located just above the lower threaded portion, the key being arranged to have a sliding fit into a keyway extending through the total length of the inner bore of a spacing member S. To join conductors A and B of Fig. 1, and to place them in their final positions separated by spacer S, conductor A is first prepared for assembly by sliding bolt D with lock washer L in place down into pipe A until the large threaded head comes into contact with threaded block E. Assuming right hand threads are used then bolt D will be advanced to position shown in Fig. 4, by turning the bolt to the left,

when viewed looking upward at the lower end of bolt D.

The key K is now inserted and then spacer S slid over bolt D with the key K engaging keyway KS. Now, bolt D will turn when spacer S is turned.

With conductor A prepared in this way, both conductors may be in their final positions before joining.

By rotating spacer S to the left, viewed as before, bolt D will advance into block C because of the action of the threaded head in the threads of block E. Further turning to the left will then engage the lower threaded portion of bolt D with the threads of block C in conductor B. Turning spacer S still more to the left advances binding member D until the threads on its head leave those of block E and it is pulled down against lock washer L and the shoulder portion directly above E₁ of block E. Any further turning of member S then tightens the joint by the means of threads in bolt D and block C. The threads of members E and C naturally will have to be provided with threads of the same pitch, although not necessarily of the same diameter. The inner conductor shown in Fig. 2 is generally similar to that of Fig. 1, except that the bolt D may be rotated by means of a screw driver engaging in a slot SD, as well as by spacer S. Likewise, block E is slightly different in its construction, to provide for the shoulder portion for lock washer L. The binding operation of Fig. 2 is generally similar to that of Fig. 1, except that a screw driver must be used to advance the bolt D into spacer S. When the key of member D and the keyway KS are engaged, the operation is the same as that of Fig. 1, and while this arrangement is probably the simplest to construct, it of necessity requires that the conductor A must be of comparatively short length, or when conductor A can be prepared in advance so that member D is projecting, the method shown in Fig. 2 is then the best type to use. However, using this scheme with bolt D projecting, only one of the two conductors could be used in its final position before joining. If pipe A is prepared with spacer S in place on bolt D, then both pipes may be in place before joining.

Fig. 3 shows a still further modification of this invention which is especially for use in a television antenna, and in this case, spacer S is undercut to allow the threaded portion of bolt D nearer the head to enter spacer S freely, the operating of this modification being similar to that of Fig. 1, that is, spacer S is turned by hand or by means of a strap wrench.

As shown by Fig. 5, this improved joint may be used for joining pipes for fluid transmission by providing a central aperture W. Also, in cases where it is not necessary, as in the case of a transmission line, to maintain the same outside diameter, spacer S may be made hexagonal in shape, or provided with a small aperture in the side, for engaging a spanner wrench so that the wrench might be used for tightening the joint. For instance, in joining two members together spaced a distance apart, where projecting bolt heads or nuts could not be used, this joint would serve the purpose very well.

Although only a few modifications of this invention are shown, it is to be distinctly understood that the invention is not to be limited to the precise embodiments shown.

What is claimed is:

1. A transmission line comprising a conductor

composed of a plurality of separate lengths, means for joining two lengths of the conductor together, said means including a recessed and a shouldered portion at one end of each length, and a threaded portion at each of the ends thereof, a spacing member interposed between the two lengths of the conductor, a bolt having threads of the same hand and pitch as the threaded portion of said lengths, said bolt retained by the threaded portion of one of said lengths before they are joined together, said bolt located within said spacing member and having means whereby it is rotated with said spacing member to join the two lengths of the conductor together by having its threads engage one of the lengths and to disengage the threads of another length by having its head extending in said recessed portion of one of said lengths until free and seating on the shouldered portion of one of said lengths, and its opposite end threaded into the other one of said lengths when they are completely joined together.

2. A transmission line comprising a conductor composed of a plurality of separate lengths, means for joining two lengths of the conductor together, said means including a recessed and a shouldered portion at one end of each length, and a threaded portion at each of the ends thereof, a spacing member interposed between the two lengths of the conductor, a threaded bolt having a threaded end portion and a slotted head, said bolt having threads of the same hand and pitch as the threaded portion of said lengths, said bolt retained by the threaded portion of one of said lengths before they are joined together, said bolt located within said spacing member and having means whereby it is rotated with said spacing member to join the two lengths of the conductor together by having its threads engage one of the lengths and to disengage the threads of another length by having its head extending in said recessed portion of one of said lengths until free and seating on the shouldered portion of one of said lengths, and its opposite end threaded into the other one of said lengths when they are completely joined together.

3. A transmission line comprising a conductor composed of a plurality of separate lengths, means for joining two lengths of the conductor together, said means including a recessed and a shouldered portion at one end of each length, and a threaded portion at each of the ends thereof, a spacing member having a recessed portion, said spacing member interposed between the two lengths of the conductor, a threaded bolt having separate threads of the same hand and pitch as the threaded portion of said lengths, one of said separate threads being located beneath its head, the other separate thread being located at its end, said threaded bolt retained by the threads located beneath its head by the threaded portion of one of said lengths before they are joined together, said bolt located within said spacing member and having means whereby it is rotated with said spacing member to join the two lengths of the conductor together by having its threads engage one of the lengths and to disengage the threads of another length by having its head extending in said recessed portion of said spacing member until free and seating on the shouldered portion of one of said lengths, and its opposite end threaded into the other one of said lengths when they are completely joined together.

4. A transmission line comprising a conductor

composed of a plurality of separate lengths, means for joining two lengths of the conductor together, said means including a recessed and a shouldered portion at one end of each length, and a threaded portion at each of the ends thereof, a spacing member interposed between the two lengths of the conductor, a bolt having threads of the same hand and pitch as the threaded portion of said lengths, said bolt retained by the threaded portion of one of said lengths before they are joined together, said bolt located within said spacing member and having means whereby it is rotated with said spacing member to join the two lengths of the conductor together by having its threads engage one of the lengths and to disengage the threads of another length by having its head extending in said recessed portion of one of said lengths until free and seating on the shouldered portion of one of said lengths, and its opposite end threaded into the other one of said lengths when they are completely joined together, and a spring locking member interposed between the head of said bolt and the shouldered portion of at least one of the lengths of the conductor to prevent them from loosening up due to vibration.

5. A transmission line comprising a conductor composed of a plurality of separate lengths, means for joining two lengths of the conductor together, said means including a recessed and a shouldered portion at one end of each length, and a threaded portion at each of the ends thereof, a spacing member interposed between the two lengths of the conductor, a threaded bolt having a central aperture therein for passage of 10 a fluid from one length of conductor to another, said bolt having threads of the same hand and pitch as the threaded portion of said lengths, said bolt retained by the threaded portion of one of said lengths when they are joined together, 15 said bolt located within said spacing member and having means whereby it is rotated with said spacing member to join the two lengths of the conductor together by having its threads engage one of the lengths and to disengage the threads of another length by having its head extending in said recessed portion of one of said lengths until free and seating on the shouldered portion of one of said lengths, and its opposite end threaded into the other one of said lengths when 20 they are completely joined together.
